UNITED STATES PATENT OFFICE.

CHARLES H. MOORE, OF GRAFTON, WEST VIRGINIA.

BUCKET.

Application filed September 1, 1921, Serial No. 497,759. Renewed February 18, 1924.

To all whom it may concern:

Be it known that I, CHARLES H. MOORE, a citizen of the United States, residing at Grafton, in the county of Taylor and State 5 of West Virginia, have invented certain new and useful Improvements in Buckets, of which the following is a specification.

This invention relates to buckets, and has as an object the provision of a collapsible 10 bucket provided with a spout and a bail, each pivoted thereto in such a manner that when the bucket is collapsed the spout and the bail may be folded into the collapsed structure so as not to take more space than would be 15 occupied by the collapsed bucket if the pivoted elements were not present.

The device provided by the invention is of special utility for automobilists since it may be readily carried in the limited space 20 available to such users.

An illustrative embodiment of the invention is shown in the accompanying drawings, in which—

Figure 1 is a vertical central transverse 25 section showing the bucket extended;

Fig. 2 is a plan view of the bucket collapsed;

Fig. 3 is a transverse section on line 3—3 of Fig. 2.

As shown, the bucket comprises a bottom 30 section 10, with upwardly flaring sides, and a series of sections, 3 being shown, at 1, 12, 13. The structure of the collapsible bucket thus far described is such as in common use.

To the upper section 13 there is shown pivoted a spout 14 which, when in the extended position shown in Fig. 1, engages under the roll 15 formed upon the upper edge of the section 13. The nozzle 14 is 40 shown as forming a complete funnel, being closed in by a top wall 16. This nozzle may be pivoted to the upper section 13 in any desired manner, whereby it may be folded into the position of Fig. 2 when the bucket 45 is collapsed so as to fall within and below the upper edge of the upper section 13.

A desirable form of pivot is that shown, comprising a rod 17 secured to the walls of the section 13 and extending across the same 50 at a position substantially below that occupied by the rear edge 18 of the spout when in extended position. Secured to the rod 17 there is shown a bail 19 which in the extend-

ed position projects upwardly from the rod 17 and then outwardly in close parallel relation with the upper wall 16 of the spout. An ear 20 may be secured to the wall 16 of the spout and may receive the connecting end portion 21 of the bail 19.

For convenient handling of the device a 60 bail 22 is shown as pivoted at diametrically opposite points 23—24, through the upper section 13, and is of such dimension as to fall within the section 13 when the bucket is collapsed, as clearly shown in Fig. 2.

The arc within which the spout 14 swings as it is placed in position for use is such that the edge of the spout 14 will swing under the roll 15, this edge being cut, as shown at 25, upon the arc of a circle of a radius equal 70 to that of the section 13 immediately below the roll.

The bucket may be of any desired capacity and will be of very great convenience to automobilists in filling radiators, or for other purposes, being readily transportable 75 and without objectionable bulk.

Minor changes may be made in the physical embodiment of the invention without departing from the spirit thereof.

I claim:

1. A collapsible bucket comprising, in combination, telescopic sections, a spout adapted to be placed in position upon the edge of the upper of said sections when the bucket is extended and to be placed within the bucket when the sections are collapsed.

2. A bucket comprising, in combination, collapsible sections, a spout pivotally mounted upon one of said sections adapted to be 90 swung to a position of use when the bucket is extended and to be folded within said sections when the bucket is collapsed.

3. A collapsible bucket comprising, in combination, a series of upwardly flaring collapsible sections, a spout pivoted to the largest of said sections adapted to be swung to a position of use and to be folded within said sections when collapsed.

4. A collapsible bucket comprising, in 100 combination, a series of upwardly flaring collapsible sections, the outer section thereof having a rolled edge, a spout pivoted to said outer section having a portion of its edge cut upon the arc of a circle to fit said section 105 below said roll, and adapted to be swung to

a position to engage said section at such point, or to be folded within said section.

5. A collapsible bucket comprising, in combination, a series of upwardly flaring sections, a spout pivoted to the largest of said sections adapted to be swung to a position of use when the bucket is extended and

to be swung to a position within said sections when the bucket is collapsed, and a bail pivoted to the said largest section and adapted to be swung to a position within said section when desired. 10

CHARLES H. MOORE.
